I claim the ornamental design for a retaining wall block, as shown and described.

DESCRIPTION

FIG. 1 is a perspective view of a retaining wall block embodying my new design, as viewed toward the front, top and one side of the block;

FIG. 2 is a front elevational view of the block of FIG. 1;

FIG. 3 is a side elevational view of the block of FIG. 1;

FIG. 4 is a top plan view of the block of FIG. 1;

FIG. 5 is a bottom plan view of the block of FIG. 1; and,

FIG. 6 is a rear elevational view of the block of FIG. 1.
